UNITED STATES PATENT OFFICE

CARL S. WEYANDT, OF PITTSBURGH, PENNSYLVANIA

SYSTEM OF RECTIFICATION

Application filed May 2, 1930, Serial No. 449,334, and in Russia December 14, 1928.

My invention relates to electrical systems and circuits utilizing preponderantly unidirectional current derived from a source of alternating current through electric valves, particularly of that type which is not perfectly asymmetrically conducting, but which allows substantial inverse current.

It is the object of my invention to provide in such circuits and systems, arrangements, combinations of elements and devices, and particularly proportions which minimize the size and number of electric valves and which prevent undue temperature rise and prolong the life of the valves.

In accordance with my invention the number of imperfect valves in series, either one or more, is such in relation to the impressed alternating electro-motive-force that substantial inverse current would flow, except for the fact that there is effective in the valve circuit inductive reactance of such magnitude that the inverse current is controlled or determined thereby, and is less than that which would flow in the absence of the inductive reactance or upon substitution therefor of a substantially equal non-inductive resistance, and in some cases the inductive reactance may be of such magnitude that the inverse current is reduced or limited to substantially negligible value. From the combination of inductive reactance, suitably related in magnitude to the circuit and the purposes for which the rectified current is utilized, with small or reduced number of imperfect valves in series, as aforesaid, arise advantages, among which are the following:

(a) The electrical losses in the valve structure itself are materially reduced, thereby enhancing the efficiency of the system.

(b) For a given number of valves in series, either one or more, a higher impressed alternating electro-motive-force may be employed, or for a given impressed electro-motive-force fewer valves in series may be utilized, maintaining adequate rectification, and without overheating or rapid deterioration of the valve structure.

(c) Without overheating or rapid deterioration of the valve structure it may be small-er for a given load current, or for a valve

structure of a given size, greater load current may be passed therethrough, and in either case the current passed by the valve structure may be greater per unit of area of its rectifying surface.

55

(d) Without overheating or rapid deterioration of valve structure of given size, it will pass a greater amount of electrical energy or power; or for passing electrical power or energy of certain magnitude smaller valve structure may be utilized.

(e) Notwithstanding the smaller number of valves in series the rectification is adequate because the ratio of the direct or preponderating current impulses are suitably large in comparison with the inverse current impulses, the ratio of the direct or forward current to the inverse current being of any suitable magnitude, generally at least two, and, in most cases, several or many times that figure.

(f) Notwithstanding the small number of valves in series, the inverse current may be made substantially negligible by the effect of the inductive reactance, so that, as regards very small magnitude of inverse current there may be procured by the combination of inductance with small number of valves in series practically the same condition or result obtaining when so great a number of valves in series is employed that the inverse current is negligible solely by the action of the valve structure itself, it being then a matter of indifference whether or not inductance be present, since the valve structure has of itself already greatly reduced or substantially eliminated inverse current.

(g) The ratio of the reactance to resistance of the valve circuit, and more particularly the ratio of the reactance to the resistance external to the valve structure, may be less than, equal to or greater than unity, depending upon circumstances and upon the uses to which the valve circuit is put.

(h) The voltage drop across the valve structure, for a given load current, is materially reduced, and generally that voltage drop is materially less than the voltage drop across the remaining impedance of the circuit. The fall of potential across the im- 95 100

pedance external to the valve structure may be less than, equal to or greater than the fall of potential across the valve structure itself, but generally, and for high efficiency, the 5 fall of potential across the impedance external to the valve structure is at least four, and preferably more than four, times the fall of potential across the valve structure itself.

(i) When the valve structure is of that 10 character in which the inverse current rapidly increases with small increase of inverse voltage, the inductive reactance may be of such magnitude as to limit the inverse current to a value below that at which it so rapidly increases, preventing undue temperature 15 rise or rapid deterioration, and reducing inverse current losses otherwise occurring.

(j) The cost of the valve structure and the 20 space occupied thereby are materially reduced for a given duty, or for the same electric power, energy or current transmitted therethrough.

Further in accordance with my invention the inductance, whose reactance is effective 25 as aforesaid in the valve circuit, may be either wholly or in part either a working or an idle inductance, in the sense that it may be either inductance of or occasioned by electromagnetic structure utilized to perform me- 30 chanical work, or an inductance which itself performs no mechanical work but nevertheless modifies, limits or controls the current transmitted by the valve structure to the actual or useful load. The resistance com- 35 ponent of the circuit impedance, of which the inductive reactance is the other component, may be constituted largely or substan- tially entirely by the ohmic resistance of the inductance winding, or may be some other 40 resistance in the circuit, for example, that of a non-inductive load.

In accordance with one of the aforesaid aspects of my invention, and in contrast with prior practice, the ratio of the impressed 45 electro-motive-force to the number of valves in series in the circuit is materially increased, in some cases as many as from five to ten times; and as the ratio of reactance to resistance increases, this figure of comparison in- 50 creases.

Further in accordance with my invention the valve structure is or may be subject to artificial or forced cooling materially to increase the current, power or energy trans- 55 mitted by the valve structure, all without overheating or rapid deterioration of the valve structure, or materially to increase the current per unit area of rectifying surface.

This application is a continuation in part 60 of my application Serial No. 290,668, filed July 5, 1928.

My invention resides in a method and features of structure, arrangement, combination and proportionment of the character herein- 65 after described and claimed.

For an understanding of my invention and for an illustration of some of the various forms it may take, reference is had to the accompanying drawings, in which:

Fig. 1 is a diagram of a circuit arrangement 70 illustrative of one of the embodiments of my invention, characterized by the fact that the magnetic field of the inductance performs mechanical work.

Fig. 1a is a diagram of a modified circuit 75 arrangement illustrating alternately energized inductances operating upon a movable core.

Fig. 2 is a diagram of a circuit arrangement 80 illustrative of another embodiment of my invention, characterized by the fact that the inductance is idle, as regards performance of mechanical work and in which the useful load is an arc, resistance of other type 85 of load.

Fig. 3 is a diagram of a circuit arrangement 90 illustrative of another embodiment of my invention, characterized by the fact that the inductance is idle, as regards performance of mechanical work, and the load is non-inductive, and capable of exerting a counter electro-motive force, such for example as a storage battery to be charged.

Fig. 4 is a diagram of a circuit arrangement 95 for a vibratory signal embodying my invention.

Fig. 5 is a characteristic curve of a cuprous oxide valve or rectifier cell.

Fig. 6 is a characteristic curve of a series 100 of cuprous oxide valves or rectifier cells.

Fig. 7 is a characteristic curve of a solid electrolytic valve.

Fig. 8 comprises a plurality of curves illustrative of electrical characteristics of my 105 invention.

Fig. 9 is an oscillogram illustrative of the application of the characteristics illustrated by Fig. 6.

Fig. 10 is a comparative oscillogram.

Referring to Fig. 1, A represents a source 110 of alternating current which term herein includes both current and voltage of simple sine wave form, or of any complex form having numerous sine wave components of different amplitudes and frequencies.

In circuit with the source A is an inductance L such as a winding of an electromagnet, solenoid or other electromagnetic structure having a magnetizable core or other element C moved or actuated by the current through L to perform useful mechanical work; inductance L is connected in series with one, or a number of serially connected, electric valve or valves V, of suitable type.

In parallel with the valves V are similar 125 valves V1, serially connected with each other and in series with inductance L, the parallel relation being employed to effect a suitable current density per unit of area of rectifying surface, to maintain suitably low the tem- 130

perature rise of the valves upon which their action, particularly when of the cuprous oxide type, depends.

It shall be understood that the valves contemplated by my invention may be of any of the following types, having in common the characteristic of permitting substantial inverse current flow:

Type "a", comprising a couple formed of a metal and an oxide thereof; which type includes others having substantially similar characteristics; for example, and preferably, copper and cuprous oxide, generally of the character disclosed in Letters Patent No. 1,640,335, Grondahl. Valves of this type, and their equivalents, exhibit little or no polarization, in contrast with electrolytic valves, and have a current conducting characteristic similar to that of simple resistance, and in some cases at least decrease in resistance with rise in temperature. It is a further characteristic of the copper-cuprous oxide rectifier that it deteriorates or ages, the more rapidly the higher its temperature, with resultant loss of its property of asymmetrical conductivity or rectifying action.

Type "b", solid or dry electrolytic rectifiers, such for example as marketed by Benvwood-Linze Company; and type "c", electrolytic rectifiers whose electrolyte is liquid, such as a solution of sulphuric acid, with which are associated electrodes of suitable materials, generally dissimilar. Both solid and wet electrolytic rectifiers exhibit polarization.

Type "d" valves comprising silicon-carbon or equivalent couples, or couples of the character described in Patents 1,751,360 to 1,751,363 and 1,751,460, or their equivalents.

The following description will be, for the sake of brevity, largely in connection with type "a" rectifiers, which is at present the preferred type for the purposes of my present invention, and is the type illustrated in Figs. 1 to 4 inclusive.

Returning to Fig. 1, it will be understood that the reactance of the inductance L and of any other inductance in circuit is in magnitude suitably related to the number of valves in series, to the resistance of the circuit external to the valves, and in general to the characteristics of the circuit, to procure the performance and effects herein described.

It is desirable with valves, particularly type "a", that their temperature rise be limited, and this may be effected by cooling in any suitable way. In Fig. 1 the pipe 1 delivers air or other suitable medium through the several nozzles 2 upon and at suitable portions of the valves, at suitable rate to maintain their temperature within desired limits. This cooling structure represents generically any suitable cooling means, particularly by fluid flow occurring either by convection or forced.

It will of course be understood that where the operation of the device is intermittent or not prolonged, forced cooling may be omitted, as it may also under all circumstances when the current density per unit area of rectifying surface is desirably low. To obtain low current density per unit area of rectifying surface, valves may be connected in parallel as indicated in Fig. 1 or the rectifying areas of the individual valves may be made correspondingly larger.

Referring to Fig. 1a, the arrangement is generally the same except that two inductances L and L₁ are employed to move the core C in opposite directions, as for example in a reciprocating electric motor generally of the type illustrated in my prior Letters Patent No. 1,637,717, August 2, 1927. Different groups of valves are associated respectively with the coils or inductances L and L₁, and are reversely related in their connections to the source A whereby prepolardating or core-actuating impulses are alternately delivered to the coils L and L₁.

In arrangements of the general character of Figs. 1 and 1a, the number of valves in series, either one or more, is such that in the absence of the inductance a substantial inverse current would flow.

As contrasted with cases where the number of valves in series is such that without inductance, and by the valves themselves, little or no inverse current would flow, my arrangement dispenses with a considerable portion of the valves in series and substitutes therefor inductance, which by its reactive effect determines what shall be the magnitude of the inverse current, imparting thereto a suitable magnitude which will not cause overheating of the valves and their rapid deterioration. The inductance serves the purpose also of permitting greater current to be transmitted through the valves without overheating, for example, .4 ampere per square inch of rectifying surface when the valves, type "a", are cooled by convection, as by contact of the air with the valve disks themselves or with radiating fins attached to or comprising a part of the valve structures. With artificial or forced cooling this current density may be readily doubled, and in general, the greater the artificial cooling the higher the current density. Either with or without forced cooling the temperature

should preferably not exceed 140° F.

It is preferable in an arrangement of this character also that the ratio of the inductive reactance to the resistance of the circuit external to the valve structure be greater than unity and in fact in some instances as high as 20, though it will be understood that the ratio of unity or even less than unity may, according to circumstances, be utilized.

By utilizing inductance, as described, with a reduced number of valves in series, the

losses in the valve structure are materially reduced, with consequent increase in the efficiency of the system. Generally, and preferably, in an arrangement of this character, the fall of potential across that portion of the circuit external to the valve structure is greater than unity, and preferably several times that figure. In addition, the ratio of the direct or forward current to the inverse current, is greater than 2 and generally several times that figure. In the case of reciprocating motors, such as shown in Figs. 1 and 1a, and in some other relations, it is desirable that the inverse current be not reduced to too small a magnitude, but on the contrary that it be large enough to perform a useful function, such as demagnetization, of parts previously magnetized by the forward current or preponderating impulses.

In Fig. 2 a step-down transformer T intervenes between the source A of alternating current and the circuit including the group of valves V in parallel with the group of valves V1. In series with the valves is an idle inductance L, and the useful load has the characteristic of a resistance and as specifically indicated is an arc a , such for example as may be utilized in welding, and utilizing for example 200 amperes. In this case the inductance L performs no mechanical work but imparts to the valve circuit a characteristic essential in accordance with my invention. The magnetic circuit of the inductance L may be complete or closed, or as indicated may have a series air gap. For the purpose of my invention the material for the magnetic core of the inductance L is preferably one having high magnetic retentivity, characteristic of some steels or alloys thereof, and particularly high carbon steel, or tungsten alloy steels and equivalents. Such core material may be used for any of the inductances contemplated by my invention when it is particularly desired that the persistence of the direct or forward current wave through the valves shall have particularly long time duration. It will of course be understood that double wave rectification may be applied in Fig. 2 by using another group of valves reversely connected with relation to the current supply and the load.

The inductance in the arrangement of Fig. 2 is again of a magnitude which determines or controls the magnitude of inverse current, when in series with a number of valves such that, in the absence of the inductance, substantial inverse current would flow. The impressed voltage, that delivered by the secondary of the transformer T, is such that the voltage per valve, or impressed voltage divided by the number of valves in series, is higher than in prior practice. While the transformer T may be used, as described, it should be understood that it is not essential and may be omitted, though the number of

valves in series will be greater because of the greater impressed voltage, though the number in series will still be such that the inductance determines the magnitude of inverse current. In an arc circuit the inverse current may be reduced by the effect of the inductance to vary small magnitude, which implies a relatively high inductive reactance.

Here again the cooling of the valves may be forced, as indicated, though it should be understood that forced or artificial cooling is not essential. By recourse to forced cooling however, the permissible current density may be materially increased, as hereinbefore described, the temperature in any event being restrained substantially below 140° F. for type "a" valves.

In this circuit arrangement again the electrical loss in the valves themselves is smaller than in the case where that number of valves in series is employed which, by valve action alone, in the absence of inductance, restricts the inverse current to insubstantial or negligible magnitude. While the impressed voltage per valve is in this circuit arrangement higher as permitted by employment of inductance, nevertheless the number of valves in series in the arc circuit is generally not so much reduced as in circuit arrangements such as those shown in Figs. 1 and 1a, and others herein described. Nevertheless, particularly where large currents are involved, as of the order of 200 amperes, requiring very large valves or a large number of small valves in parallel, the saving of only one or two in series, by recourse to the inductance, is of great advantage in reducing the total size and cost of the valve structure.

In Fig. 3 there are again shown two groups of valves V and V1 in parallel and in series with an inductance L, which may be of the character of the inductance L with its core, described in connection with Fig. 2, utilized for charging a storage battery S or for supplying current to any other device having both a resistance characteristic and exhibiting counter electro-motive-force. For example A may deliver alternating current at 60 cycles and at a pressure of 110 volts. The storage battery S of three cells may then be suitably charged by the utilization of about three types "a" valves in series. In this case the impressed voltage per valve is approximately 33, under which circumstance, without the inductance L, the inverse current would be large indeed, and the heating effect disastrous to the valves themselves. In this instance, the inductance L is a substitute for a considerable number of extra valves in series that would be necessary suitably to limit the inverse current, in the absence of inductance. As in all other cases herein described, artificial or forced cooling of the valves may be resorted to. In this case, and the others described, and in general, the effect of the

- inductance operates cumulatively with the cooling medium to maintain the temperature of the valves within their safe working limits, giving them prolonged life, the inductance in addition permitting larger load currents for a given size of valve structure and permitting a greater impressed voltage per valve than in prior practice.
- Referring to Fig. 4, there is illustrated an electric trembler or vibrator bell, buzzer or equivalent signaling instrument comprising the gong 3 struck by clapper 4 carried by the armature 5, biased toward stop 5a, of the electromagnet whose core 6 is provided with the magnet windings 7, 7 in series with which across the terminals of the source A is a valve V and control switch or push button b. When the inductance of the windings 7, 7 is sufficiently high, the bell or signal may be operated with a single valve V, or a few valves V in series, of type "a" from a source A delivering current at a pressure of 110 volts. Here again the number of valves in series is small, as permitted by the inductance, of the windings 7, 7, which determines and controls the inverse current. A device of this character operates intermittently or infrequently, and accordingly forced or artificial cooling is rarely if ever necessary; and, insofar as concerns heating effect, the relation of inductance to number of valves in series, their size, and the current transmitted by them, need not be so carefully or nicely related as in the case where the apparatus operates for long periods or continuously, though in no event should the inverse current or heating effects be so large during the short periods of operation that the valve structure deteriorates or ages at a too rapid rate.
- Vibratory structure of this general character may also be utilized for massage implements, on a larger scale where the electromagnetic system is employed to operate screens of sieves, or to tap foundry molds, either when the operation is intermittent or prolonged. Where use is continuous or prolonged artificial or forced cooling may be resorted to, though not essential.
- The voltage-current characteristic of a type "a" rectifier, particularly the copper-cuprous oxide rectifier, such as now known to the trade as Rectox or Kuprox, is indicated in Fig. 5 wherein ordinates are current magnitudes in amperes and abscissæ are electro-motive-forces in volts. Through a single disk or valve was passed, in a non-reactive circuit, current from a direct current source. The portion of the characteristic curve extending from the origin O upwardly to the right, represents the relations of current to voltage across the terminals of the cell or disk for conduction from the oxide to the copper, and is the current of that direction which gives the largely predominating current in circuits of the character hereinbefore referred to. It

is noted that the resistance to flow of current from oxide to copper indicated by this portion of the characteristic, is represented at every point thereof by the quotient of the voltage divided by the current. The resistance to current flow in this direction is low and, except for temperature effects, is fairly constant. The temperature coefficient is up to a certain point negative, the resistance falling slightly with temperature rise; beyond that point, where the current density and heating effects are of certain magnitudes, the valve has a positive temperature coefficient of resistance. The portion of the characteristic to the left of the origin O and below the horizontal axis indicates a high resistance to conductivity or current flow in the inverse or reverse direction from zero to two or three volts, with a rapidly decreasing resistance however thereafter, due to the temperature rise caused by the losses of electric power, represented by the product of the resistance into the square of the current. The characteristic shows that because of the negative temperature coefficient of resistance, the inverse current rapidly increases with small increases in the impressed voltage, tending to aggravate the condition of temperature rise. Because of the great difference in the resistances for the positive and inverse directions of conduction, and particularly from zero to two or three volts applied in the inverse direction, the watt losses due to the large and preponderating direct or positive current impulses are not great because the resistance for conduction in the positive or direct sense is low while for relatively smaller inverse currents the watt losses are greater than for the relatively great current passed in the positive or low resistance direction. In the example illustrated this high wattage loss begins to occur from upwards of three or four volts inverse, and it is therefore desirable to maintain conditions that will restrain the inverse current and voltages to magnitudes of the order of one tenth of an ampere and two or three volts, for the particular cell, disk or valve in question which had a rectifying surface of about three and one-half square inches, as represented by an oxide covered disk or plate about two inches square. The characteristic indicates that for the currents corresponding to inverse voltages of about 4.8 and 5.3 the disk or valve partook of temperatures of 127 and 158 degrees Fahrenheit, respectively. At least the higher of these temperatures was for this particular valve too high and caused its rapid deterioration or aging, causing it soon to lose its rectifying power or valve action. In general for type "a" valves, without forced cooling, the temperature should not, for steady use and long life, exceed about 140° F. By way of example merely as capable of illustration by Fig. 5, it is desirable to keep

70

120

125

130

the inverse current below magnitudes corresponding with inverse voltages of about five volts, and generally less. It will be understood however that this will depend upon the excellence of the valve as manufactured and in some cases this permissible inverse voltage may materially exceed five volts. In general it is desirable to operate below such inverse current values as correspond with a rapidly increasing current with small increase of inverse voltage, and this is effected by the inductance, in circuit with the valve or valves, which limits and determines the inverse current.

16 In Fig. 6 is given a characteristic taken under similar conditions for three of the copper-cuprous oxide disks or cells in series with each other. The characteristic to the right and above the origin O is generally similar to that of Fig. 5 and that below and to the left of the origin O is also generally similar to that of Fig. 5, except that it is not carried to the above mentioned extreme or undesirable conditions. This characteristic, for conduction in inverse or reverse direction indicates that for three cells in series the voltage applied in inverse direction should not materially exceed about 15 volts, to maintain suitable and desirable temperature conditions.

Fig. 7 is a generally similar characteristic curve of a Bennwood-Linze dry electrolytic valve, two cells in series, non-inductive circuit, alternating current source. To the right and above the origin O the characteristic 8, in solid line, for the building current, current increasing from zero to a positive maximum, and the characteristic 9, in dotted line, for the decaying current, diminishing from the positive maximum to zero, are both generally similar to the characteristic to the right and above the origin O in Figs. 5 and 6, indicating relatively low resistance for conductivity in the direct or positive sense. To the left and below the origin O the building current, or current increasing from zero to a maximum in the negative or inverse direction, is indicated by the solid line curve 10 and the decaying inverse current is shown by the dotted curve 11. These two also are generally similar to the inverse current characteristic of Figs. 5 and 6; and as in the case of the copper-cuprous oxide type of valve it is desirable to keep the inverse current within suitably small limits to prevent excessive losses and temperature rise.

With imperfect valves in general, and particularly those of the types hereinbefore referred to, and especially type "a", there is used, in substitution for a part of the whole number of valves in series necessary, for a given impressed voltage, to limit the inverse current to insubstantial or negligible magnitude, an inductance which determines, controls or limits the inverse current to a mag-

nitude which may be insubstantial or negligible or which may be substantial, but in all cases less than that obtaining when the inductance is absent, or when for the inductive reactance there is substituted an equivalent non-inductive resistance.

When so utilizing fewer valves in series, either one or more, the inductance may be of such magnitude as to procure a desired ratio of forward or direct current to inverse current (root means square values, such as measured, for example, by an ammeter of the electro-dynamometer type); to cause the fall of potential across the impedance of the circuit external to the valve structure, greater than, equal to or less than the fall of potential across the valve structure; to control the magnitude of losses in the valve structure; to effect a ratio of reactance to resistance in the circuit external to the valve circuit, greater than, equal to or less than unity; to increase the current density in the valve structure without overheating; to permit transmission of greater power, energy or current through a valve structure of a given size without undue heating; and in general to prevent undue temperature or rapid deterioration of the valve structure.

The aforesaid ratio of reactance to resistance of the circuit external to the valve structure may in many cases be substantially greater than unity, as, for example, from 5 to 20 or more. In cases such as generally illustrated by Figs. 1, 1a and 4, this high value of the ratio may obtain. Ratios materially greater than unity and of the order of 10 or 20 may be utilized also in the case of charging storage batteries in a circuit arrangement generally illustrated by Fig. 3. In the case of battery charging the inductance or reactor has the further function of suitably limiting or regulating the charging rate of the battery. In the case of arc or arc welding circuits, such as generally illustrated by Fig. 2, and in which generally the current is of high magnitude, the ratio of reactance to resistance, external to the valve structure, may be approximately unity, and in some cases less than unity.

In general where the inductance is a working inductance, illustrated generally by Figs. 1, 1a and 4, this ratio of reactance to resistance is generally at least unity and generally and preferably many times unity. In general, in the case where the inductance is idle, or not a working inductance, and the load has relatively high ohmic resistance, for highest efficiency the ratio of reactance to resistance will generally be less than or approximately unity.

The ratio of the root means square forwarded direct current to root mean square inverse current is generally greater than 2 and may be 4 to 6, or higher.

The efficiency of operation is the higher as

the ratio of the fall of potential across the impedance external to the valve structure is higher; and this ratio in some instances may range upwardly to a magnitude of the order of 10.

Fig. 8 comprises characteristic curves illustrative of the choices of relations of circuit factors and conditions which may be resorted to to effect the results contemplated by my invention.

Ordinates are magnitudes of the ratio of positive or direct current, root mean square value, to negative or inverse current, root mean square value; and abscissæ are magnitudes of the expression or ratio

$$\frac{RK}{X}$$

in which R is the non-inductive resistance of the circuit external to the valve or valves; X is the total inductive reactance of the circuit; and K is the voltage drop (root mean square values, both direct and inverse) across the impedance external to the valve or valves, divided by the number of cells or valves in series. If however K represents line voltage divided by the number of cells or valves in series, each characteristic curve will be of the same type, to wit, in a broad sense hyperbolic, but will be displaced somewhat from the corresponding curve of Fig. 8. Furthermore in the foregoing expression K is itself

proportional to $\frac{X}{R}$.

Of Fig. 8 the curve 12 applies to a copper-cuprous oxide valve or several of them in series, of the present Rectox or Kuprox type manufactured respectively by the Westinghouse Electric & Manufacturing Company and by Kodel Manufacturing Company, Cincinnati, Ohio.

Curves 13 and 14 apply, respectively, to wet electrolytic and dry electrolytic rectifiers.

Referring to curve 12, and assuming a ratio of direct to inverse current of 7, the corresponding value of

$$\frac{RK}{X}$$

is 3.5, which, for an assumed value of

$$\frac{R}{X}$$

equal to 0.1, gives a value for K equal to 35 which is the number of volts per cell or valve found by dividing the voltage drop across the impedance external to the valve or valves by the number of valves in series. Assuming a certain efficiency, in terms of voltage drop, and assuming a line voltage of 110 volts, the voltage drop across the load or impedance external to the valve or valves is 0.9 times 110 or 99 volts which, divided by 35, gives 65 roughly a value of K corresponding with

three valves or cells in series. If the individual valves be of large enough surface as regards active rectifying area, for the magnitude of the load current, i. e. root mean square value of both positive and inverse currents, paralleling of the valves will be unnecessary. This is the case for example for Rectox and Kuprox valves operated at a current density of about $\frac{1}{3}$ of an ampere per square inch of rectifying area, at which current density without forced ventilation or cooling, the temperature attained will be within desired limits. For example if the individual valves have one square inch of rectifying area, and the load current, aforesaid, shall be one ampere, the rectifying valve system will comprise 9 cells or valves, 3 in parallel and 3 in series.

Each of the curves 12, 13 and 14 is expressible in an algebraic formula which may be utilized in lieu of the curves themselves in the manner above indicated. The equation will be of the general form of

$$\frac{y^x}{x} = Z, \quad 90$$

in which Z is a constant depending upon the characteristics of the valve and which, for copper-cuprous oxide valves is of the order of 250, for wet electrolytic valves is approximately 800, and for dry electrolytic valves is of the order of 100 to 125; y represents ratio of root means square values of direct to inverse current; x represents the aforesaid relation

$$\frac{RK}{X},$$

and n is an exponent of a magnitude depending upon the characteristics of the valve, and for copper-cuprous oxide valves has been found in some instances at least to be greater than 2 and of the order of 2.2, and approximately 1.2 and 4 for wet and dry electrolytic valves, respectively. However the characteristic curves of Fig. 8 suffice as a means for determining the magnitude of various essential circuit factors.

The point on any of the curves of Fig. 8 selected for operation depends upon the desired ratio of forward or positive current to inverse current. If that ratio is first chosen, then the corresponding point on any of the curves will give by reading downwardly to the axis of abscissæ the corresponding approximate value of

$$\frac{RK}{X}$$

and the several factors of this expression may then further be selected or chosen, particularly R and X, suited to the particular purpose for which the valve of selected type is to be used. Conversely, with

$\frac{RK}{X}$

chosen, the resultant ratio of forward to inverse current will be approximately indicated.

Fig. 9 comprises oscillograms of a circuit operated from a 110 volt 60 cycle supply, containing 20 ohms inductive reactance, 2 ohms non-inductive resistance external to the valves, 3 Kuprox valves in series, 6 in parallel, each having a rectifier plate or disk about 2 inches square, with an effective rectifying surface of about $3\frac{1}{2}$ square inches. Ordinates are magnitudes of voltage and current, and abscissæ represent time intervals.

The curve F represents the sinusoidal impressed or line voltage; I^+ represents the current in the direct or positive sense, having a duration, in practice, of from about 270 to about 290 electrical degrees; I^- represents the inverse current; E^+ represents the positive fall of potential across the impedance external to the valves; E^- represents the negative fall of potential across the terminals of the impedance external to the valves; e^+ represents the positive fall of potential across the terminals of the valves in series; and e^- the negative fall of potential across the terminals of the series of valves. These oscillograms are not to scale, but are approximately correct and illustrate the reactions and effective proportions of circuits embodying my invention.

Fig. 10 comprises curves relating to the same circuit described in connection with Fig. 9. In it the curve having the positive and negative components, respectively, I^+ and I^- is for one coil of an electric hammer or reciprocating motor having the aforesaid reactance of 20 ohms, with the core reciprocating in synchronism with the line current. The curve i^- is that of the inverse current when the core of the hammer was held in fixed position corresponding with minimum magnetic circuit reluctance, the component I^+ being substantially the same for both conditions of core reciprocating or fixed. Comparison of I^- with i^- shows the influence of movement, of any portion of the magnetic circuit of an inductive reactor, upon, generally in reducing, the inverse current. The dotted curve whose positive and negative components are indicated at n^+ and n^- , respectively, represents the current magnitudes when for the reciprocating motor or hammer winding is substituted a non-inductive resistance or non-reactive load of substantially the same number of ohms as the impedance of the hammer winding, the valve structure being the same as before. This dotted line curve shows first that the current is strictly in phase with the electro-motive-force and secondly that the

negative or inverse current has a peak value of 76% of the peak value of the positive current wave represented by n^+ , and the root mean square negative or inverse current is many times larger than the root mean square inverse or negative current I^- or i^- . Furthermore the peak value of the current i^- , corresponding to an idle inductance in the circuit, is about 24% of the peak value of the current I^+ , and the peak value of the curve I^- , for a working inductance, is about 16% of I^+ . Obviously the heating effect of either current I^- or i^- is small compared to n^- and hence the aging effect upon the valve is enormously reduced by the employment of inductance with small number of valves in series, and in addition the ratio of the positive or direct to the inverse current is many times greater for I^+ than for n^+ .

By way of example of proportions falling within my invention, and more particularly relating to a two coil reciprocating motor or hammer, as illustrated in Fig. 1a, each of the hammer windings or inductances L had a reactance, at 60 cycles, of 44.9 ohms; the resistance of each coil circuit external to the valves, of the copper-cuprous oxide type, was 2 ohms, corresponding to a ratio of reactance to resistance of about 22.5. The root mean square current in the positive or direct sense was 1.9 amperes through each coil or inductance; the root mean square negative or inverse current was 0.27 ampere. There were 2 valves V and VI in series with each coil, 2 valves in parallel. Each individual valve had an effective rectifying surface of about 3.5 square inches. The current density of rectifying surface was of the order of $\frac{1}{3}$ ampere per square inch, with a line voltage of 110 volts. The temperature of the valves remained sufficiently low, well below 140° F., without air blast or other artificial cooling. The hammer or reciprocating motor was utilized to drill holes in concrete or stone and to chip or cut concrete, metal or stone, at or higher than its usual rated capacity when previously used in connection with thermionic valves.

I have also operated the same reciprocating motor or hammer, from a 60 cycle 110 volt circuit, with 10 copper-cuprous oxide valves in series, reactance 90 ohms, resistance 8 ohms external to valves. This relation also is within my invention.

A single copper-cuprous oxide valve in series with each coil of a two coil reciprocating motor or electrical percussive tool of the same type has also been used by me on a 110 volt alternating current circuit. This also is within my invention.

The reduction in number of valves in series with the windings of reciprocating motors, such as described in the foregoing examples, increases the efficiency of the valves

and of the circuit or system, and in fact increases the mechanical output of the motor, for a given amount of electric energy consumed, over my prior practice in which thermionic valves were utilized. Furthermore, with reciprocating motors of the character specified in the foregoing examples, the efficiency was reduced, as from about 15% to 20%, when the number of valves in series was increased to that number which by the valve action itself and without substantial benefit from inductance, the inverse current was small or insubstantial.

For an electric bell system such as shown in Fig. 4, I have operated the same from a 60 cycle 110 volt circuit through 2 valves V in series of the copper-cuprous oxide type, each having a rectifying surface of about 2 square inches. The magnet winding had a reactance of 1090 ohms at 60 cycles, and the resistance of the circuit external to the valves was 50 ohms, giving a reactance to resistance ratio of about 22. I have also utilized, at 10 volts, and briefly at 110 volts, one copper-cuprous oxide valve in series with a bell winding 7, 7 whose reactance at 60 cycles was 15.2 ohms and the resistance 1.4 ohms, giving a reactance to resistance ratio of about 11, the valve having a rectifying surface of about 2 square inches. This combination also is within the scope of my invention.

It will be understood that such a valve-inductance relation as indicated in Fig. 4 has wide application. For example it may be used for high power systems as when the electromagnet 7 is utilized to vibrate a screen or sieve, to tap a foundry mould, etc.

In circuits of the characters described, in which the inductance may be in whole or in part a working inductance, and of the general character of Figs. 1, 1a and 4, in general the ratio of the inductance to resistance of the circuit, or the ratio of the inductive reactance to resistance of the circuit external to the valve structure, may be anything suitable or desirable, but is generally greater than unity, and may be as high as 20 or more, the number of valves in series being that generally herein described. When the circuit is not operating continuously, but only infrequently or intermittently, and where considerations of efficiency are not important, or where only low power is involved, the aforesaid ratio may have a magnitude lying within the lower range of values, and yet only a low number of valves in series need be used.

An arc circuit, generically indicated in Fig. 2, is generally itself a low voltage circuit, including the case of arc welding where very large current at low voltage is utilized. For this purpose a step-down transformer T may be utilized, serving merely to procure a magnitude of voltage impressed upon the arc circuit which is suited thereto; the trans-

former T may be omitted however with the employment of more valves in series, though still reduced in number when compared with the voltage of the circuit A. Notwithstanding the employment of the transformer T, the number of valves in series is small compared to the voltage delivered by the transformer secondary.

Where the arc a is used for welding, the current may have a magnitude of 200 amperes or more, requiring for each valve in series, a great number, as one hundred or more in parallel, particularly when of the cuprous oxide type of usual size.

In such a circuit, generically represented by Fig. 2, the voltage drop across the welding arc itself is low, but nevertheless this voltage drop is generally substantially the entire or a very large portion of the entire voltage drop in the circuit external to the valve structure, and the voltage drop across the arc or external circuit may sometimes be less than the drop of voltage across the valve structure itself, comprising a number of valves in series with a great number in parallel. In general, however, the voltage drop across the valve structure is about equal to or less than the voltage drop across the arc or circuit external to the valve structure.

In the case of an arc welder, it is from some standpoints desirable to have a high ratio of reactance to resistance external to the valve structure. On the other hand, in the case of arc welders or other circuits where the current involved is of a high order of magnitude, implying a great number of valves in parallel or what may be termed large valve structure, this ratio of reactance to resistance may be considerably smaller, as of the order of unity, or even less than unity, to permit further reduction of the number of valves in series, because for each valve in series that may be dispensed with, there may be a saving of one hundred or more valves in parallel, particularly in the case of cuprous oxide valves. Presence of inverse current under such circumstances is not altogether disadvantageous, and generally the saving in cost of valve structure is more important.

In charging storage batteries, generically indicated by Fig. 3, it is preferable that, with the low or reduced number of valves in series, as herein described, the inductance be great enough in magnitude to maintain the inverse current quite small or negligible, particularly since it is only the forward current that effects charge of the battery. It will be understood, however, that lower magnitudes of inductance are comprehended within my invention provided the inductance supplants a portion of that number of valves in series which would of themselves maintain the inverse current insubstantial or negligibly small. It will further be understood that while in Fig. 3 there is illustrated single wave

rectification, that double wave rectification may be utilized. However, single wave rectification generally suffices, particularly where so high inductance is used, with reduced number of valves in series, that the inverse current is insubstantial or negligibly small.

By way of example, in a system of the general character illustrated by Fig. 3, where the 10 battery S is a so-called 6-volt battery, and the electro-motive-force impressed from the line A is 110 volts, 60 cycles, the inductive reactance of the circuit, wholly or principally L, may be 35 ohms, and the resistance of the 15 circuit external to the valve structure 1.8 ohms, giving a ratio of reactance to resistance of about 19, the current being about 2.5 amperes with three valves of the cuprous-oxide type in series, and a suitable number in parallel to carry the current in question without overheating or deterioration. In such a case, the inverse current is insubstantial, the cost 20 of the inductive reactor, as L, under these circumstances would be less than half the cost of the transformer necessary to step down the 25 line voltage; and because of the few valves in series, the cost of the valve structure is of the order of half that of systems commonly employed. For purposes of comparison it may 30 be stated, that in one instance of common practice, utilizing cuprous-oxide valves, for charging a 6-volt storage battery, charging current 1 ampere, there has been utilized a transformer for stepping down the line voltage 35 to a secondary pressure of 6 volts, with 4 valves in series, 2 in parallel, in each side or branch of a double wave rectifying system, requiring a total of 16 valves; whereas, the maximum number of valves required in accordance 40 with my invention, would be 8. In another instance, for charging a 6-volt storage battery at 4 amperes charging rate, with a step down transformer, 4 cuprous-oxide valves were utilized in series, with 4 in multiple in each branch or side of the full wave 45 rectifying system.

In general, in battery charging, the ratio of reactance to resistance is preferably high, as, for example, from about 15 to about 20, particularly in the case of single wave rectification.

In the case of cuprous-oxide valves, such as the Rectox and Kuprox hereinbefore referred to, the current density, by recourse to 55 my invention, may be one-third of an ampere or higher, as .4 ampere, per square inch of rectifying surface, without artificial or forced cooling; i. e., when the valves are either supplied with radiating fins, as in the 60 case of Rectox, or themselves are in the form of discs or fins, as in the case of Kuprox, the valves being assembled in reasonably compact groups, side by side. As commonly now produced, the valves are assembled as close 65 together as possible, and in consequence the

heat from one valve affects the temperature of the adjacent valve, causing greater temperature rise for a given current density than would otherwise be the case if there were fewer valves within the same space, or if the valves were further apart. In consequence, where fewer valves in series are employed in accordance with my invention, the greater will be the current carrying capacity per square inch of rectifying surface without 70 undue heating or deterioration.

In accordance with my invention, as stated, upwards of one-third of an ampere (total root means square value of both forward and inverse current) per square inch of rectifying surface is good practice without artificial cooling. Without overheating or deterioration, the current density is increased in accordance with my invention about 15 to 20%. While it has been common to utilize that 80 number of cuprous oxide valves in series, corresponding with about 4 volts impressed voltage per valve, and generally about 3½ volts per valve, in accordance with my invention the impressed line voltage per valve 90 is materially greater, in many cases as much as eight times that aforesaid. In the case of arc welders, however, the impressed voltage per valve is about five volts, which too is substantially greater than prior practice 95 above mentioned.

By forced or artificial cooling of cuprous-oxide valves, particularly when assembled as customary, and as above referred to, the current density may be materially increased and easily doubled, as when the cooling medium is air whose velocity is about 1000 feet per minute, in which case with a room or ambient temperature of 80 degrees F., the valves 100 will operate safely below deteriorating temperature and continuously for thousands of hours and practically indefinitely.

In the case of an arc welder system, in accordance with my invention, for 200 amperes, with the valves arranged fairly uniformly over an area of about 254 square inches, with three stacks or tiers of valves each occupying such area and with about ¼ inch space between stacks, sufficient cooling is obtained if there is passed through the valve assembly 105 1750 cubic feet of air per minute, the velocity above mentioned being that of the air as it left the stack of valves furthest from the blower or fan, the entire valve assembly being about 6½ inches deep and the blower or fan disposed about 5 inches from the nearest stack or tier.

The reactance X hereinbefore referred to and the non-inductive resistance of the circuit external to the valve are the components of an impedance which is the quotient of the root mean square value of the impressed sinusoidal electro-motive force divided by the root mean square (positive and inverse) current. The non-inductive resistance of the 115 120 125 130 135

circuit being known or readily determined, the reactance is determinable since the aforesaid quotient or impedance has become known.

5 The root mean square values of current and/or electro-motive-force hereinbefore referred to are those which are measured by two coil ammeters or two coil volt-meters, of the electro-dynamometer type, of which it is 70
10 characteristic that the stationary field producing coil is in series with the deflecting or moving coil.

For measuring the ratios of root mean square values of positive or direct current impulses to root mean square values of negative or inverse current impulses, the ratios of these direct and inverse currents being ordinates in Fig. 8, the positive or direct and inverse or negative current impulses are isolated 75
15 from each other in different circuit branches by recourse to use of perfect valves, such as thermionic valves, connected in reverse senses in branches in parallel with each other, with an ammeter in series with each, 80
20 these parallel branches being connected in series with the valve whose direct and inverse currents are to be measured, as well 85
25 understood in the art.

It shall be understood that my invention 90
30 is not limited to circuits or systems utilizing small amounts of electrical power, but is utilizable as well, by recourse to generally the relations and proportions described, where large amounts of electric power are to be 95
35 utilized and controlled, as for driving electric cars, trains, locomotives, or other loads, by motors, of the direct current type, between which and an alternating current supply intervenes valve structure of the character 100
40 herein described, a reduced or low number of valves in series being utilizable when having the benefit, as herein described, of associated inductance. Similarly, the same relations may be utilized in any other high 105
45 power circuit for any purpose, and, whether the load be inductive or non-inductive, the circuit will contain sufficient inductance to make possible the aforesaid reduced number of valves in series, and to make possible in 110
50 addition any one or more of the advantages herein described.

From the foregoing it will appear that in general, in accordance with my invention, inductance is utilized in substituton for a part 115
55 of that number of valves in series which would be necessary to reduce the inverse current to an insubstantial or negligible magnitude, the magnitude of the inductance being such as to determine the magnitude of the 120
60 inverse current, allowing it in some instances to be substantial and for other purposes restricting it to insubstantial or negligible magnitude. It is further apparent that notwithstanding the reduction of number of 125
65 valves in series, overheating or deterioration

is prevented, even when the current rating of the valve structure is increased as it may be, and, in addition, higher electrical conversion or efficiency and other advantages are obtainable; and that, in general, the cost of the 70
75 valve structure and the space occupied by it are materially reduced for a given duty.

For an impressed alternating electro-motive force of given magnitude, the impedance of the circuit, including the inductive reactance, affects or determines the magnitude of current passed by the valve structure, and the inductive reactance is of such magnitude and so operates in association with other impedance, including resistance, of the valve 80
85 circuit that, without overheating or rapid deterioration of the valve structure, it may be materially less costly for the same duty than heretofore realized; and it is smaller, for a given effect or duty, than heretofore realized, either as regards the size of an individual valve or individual valves, or as regards the number of valves in series, or in parallel, or both. It is smaller as regards the number 90
95 of valves in series when that number is less than the normal number of valves in series, that is, such that the inverse current is small or negligible without the use of inductance for determining the inverse current.

For brevity in the appended claims the 95
100 term "valve structure" comprehends either one or more valves in series, and any number in parallel; the term "imperfect" as applied to a valve or valve structure designates a valve or valve structure having the characteristic of permitting substantial inverse current, and excludes thermionic and similar substantially perfect valves which permit practically no inverse current; the term "oxide" as applied to a valve or valve structure 105
110 refers to type "a" valves, particularly copper-cuprous oxide valves; and the term "overheating" as related to the valve structure refers to that degree of heating which, in continuous, intermittent or infrequent operation, would cause rapid deterioration of the valve structure, as within about 500 to 1000 hours total use, or, in the case of copper-cuprous oxide valves a temperature thereof in excess of about 140° F. 115

What I claim is:

1. In the art of rectification by impressing an alternating electro-motive-force upon a circuit including a load and imperfect valve structure, the method of reducing the size of the valve structure for a given duty, which comprises utilizing such number of imperfect valves in series that there tends to flow an inverse current of a magnitude to cause overheating of the valve structure, and rendering the circuit inductive to a degree which limits the inverse current to a lesser magnitude which prevents overheating of the valve structure.

2. In the art of rectification by impression 130

- of an alternating electro-motive-force upon a circuit including a load and imperfect valve structure, the method of increasing the capacity of the valve structure without overheating which comprises utilizing in series such number of imperfect valves that the inverse current tending to flow is of a magnitude to cause overheating, and rendering effective in the circuit inductance of a magnitude to limit the inverse current to a lesser magnitude which prevents overheating of the valve structure. 6 70
3. In the art of rectification by imperfect valve structure in a circuit including a load and a source of alternating electro-motive force, the number of valves in series being such that the inverse current tending to flow is of a magnitude adapted to cause substantial deterioration of the valve structure, 15 80
- 20 the step which consists in rendering effective in the circuit an inductance of a magnitude to limit the inverse current to a lesser magnitude and to effect passage of greater load current, without substantial deterioration of 25 the valve structure. 85
4. In the art of rectification, the method which comprises impressing an alternating electro-motive-force upon a circuit including imperfect valve structure and a load, utilizing such number of imperfect valves in series that there tends to flow an inverse current whose heating effect with that of the forward current is excessive, and by inductive reactance limiting the inverse current 30 90
- 35 to a lesser magnitude such that with the corresponding forward current overheating of the valve structure is prevented. 95
5. In the art of rectification, the method which comprises impressing an alternating 40 100
- 45 electro-motive-force upon a circuit including imperfect valve structure and a load, utilizing such number of imperfect valves in series that inverse current of excessive heating effect tends to flow, and by inductive reactance limiting the inverse current to a lesser magnitude so related to the magnitude 50 105
- 55 of the forward current as to prevent overheating of the valve structure while conducting greater current than otherwise permissible without overheating. 110
6. In the art of rectification, the method which comprises impressing an alternating electro-motive-force upon a circuit including imperfect valve structure and a load, and 55 115
- 60 reducing the losses in the valve structure by utilizing such number of imperfect valves in series that inverse current of a magnitude which would cause substantial deterioration tends to flow, and limiting the inverse current by inductive reactance in the circuit to such lesser value that overheating and substantial deterioration of the valve structure is prevented. 120
7. In the art of rectification, the method 65 which comprises impressing an alternating 125
- electro-motive-force upon a circuit including imperfect valve structure and a load, and increasing the impressed voltage per valve by utilizing such number of imperfect valves in series that an inverse current of excessive heating effect tends to flow, and by inductive reactance limiting the inverse current to a lesser value to prevent overheating of the valve structure. 70 75
8. In the art of rectification, the method which comprises impressing an alternating electro-motive-force upon a circuit including imperfect valve structure and a load, and increasing the current density without overheating of the valve structure by utilizing in series such number of imperfect valves that there tends to flow an inverse current of excessive heating effect, and by inductive reactance limiting the inverse current to such lesser magnitude that overheating of the valve structure is prevented. 80 85
9. In the art of rectification, the method which comprises impressing an alternating electro-motive-force upon a circuit including imperfect valve structure and a load, and increasing the electrical power transmitted through said valve structure to said load without overheating of said valve structure by utilizing in series such number of imperfect valves that there tends to flow an inverse current of excessive heating effect, and by inductive reactance limiting the inverse current to lesser magnitude that overheating of the valve structure is prevented. 90 95
10. In the art of rectification by imperfect valve structure in circuit with a load and a source of alternating electro-motive-force, the method which comprises utilizing such number of imperfect valves in series that an inverse current of excessive heating effect tends to flow, and imparting to the circuit an inductive reactance of such magnitude that the inverse current is limited to a magnitude which is less than half the magnitude of the forward current and which prevents overheating of the valve structure. 100 105
11. In the art of rectification by imperfect valve structure in circuit with a load and a source of alternating electro-motive-force, the method which comprises utilizing such number of imperfect valves in series that an inverse current of excessive heating effect tends to flow, and imparting to the circuit inductive reactance of such magnitude that the inverse current is limited to a lesser magnitude which prevents overheating of the valve structure while the voltage drop across the valve structure does not exceed the voltage drop across the impedance of the circuit external to the valve structure. 110 115
12. In the art of rectification by imperfect valve structure in circuit with a load and a source of alternating electro-motive-force, the method which comprises utilizing such number of imperfect valves in series that an 130

inverse current of excessive heating effect tends to flow, and imparting to the circuit inductive reactance of a magnitude which is at least as great as the resistance of the circuit 5 external to the valve structure and which limits the inverse current to a lesser magnitude which prevents overheating of the valve structure.

13. In the art of rectification by imperfect 10 valve structure in circuit with a load and a source of alternating electro-motive-force, the method which comprises utilizing such number of imperfect valves in series that an inverse current of excessive heating effect 15 tends to flow, the valve structure being of that character in which the inverse current rapidly increases with small increase of inverse voltage, and imparting to the circuit inductive reactance of that magnitude which limits 20 the inverse current to a value below that at which it rapidly increases with small increase of inverse voltage.

14. In the art of rectification, the method which comprises impressing an alternating 25 electro-motive-force upon a circuit including imperfect valve structure and a load, utilizing such number of imperfect valves in series that there tends to flow an inverse current whose heating effect is excessive, artificially cooling the valve structure, and by inductive reactance limiting the inverse current to a lesser magnitude such that with said cooling overheating of the valve structure is prevented.

15. In the art of rectification, the method which comprises impressing an alternating electro-motive-force upon a circuit including a load and imperfect valve structure of the copper-cuprous oxide type, utilizing in series 40 such number of said imperfect valves that there tends to flow an inverse current of excessive heating effect, and effecting a current density of at least $\frac{1}{3}$ ampere per square inch without overheating of the valve structure by 45 inductive reactance of a magnitude which limits the inverse current to a lesser value to prevent overheating of the valve structure.

16. In the art of rectification, the method which comprises impressing an alternating 50 electro-motive-force upon a circuit including a load and imperfect valve structure of the copper-cuprous oxide type, utilizing in series such number of said imperfect valves that there tends to flow an inverse current of excessive heating effect, effecting a current density of at least $\frac{1}{3}$ ampere per square inch without overheating of the valve structure by inductive reactance of a magnitude which limits the inverse current to a lesser value to 55 prevent overheating of the valve structure, and artificially cooling the valve structure for materially increasing said current density while preventing overheating of the valve structure.

17. In the art of rectification by imperfect

valve structure in circuit with a load and a source of alternating electro-motive-force, the method which comprises using such number of imperfect valves in series that the impressed electro-motive-force per valve is at 70 least twice the impressed electro-motive-force per valve when the number in series is such that there is insubstantial inverse current, and by inductance limiting the inverse current to a lesser magnitude such as to prevent 75 overheating of the valve structure.

18. In a rectifying system, a source of alternating electro-motive-force and an associated load circuit including solid imperfect 80 valve structure exhibiting little or no polarization, the number of valves in series being such that there tends to flow an inverse current of excessive heating effect, and inductance in said circuit of a magnitude which limits the inverse current to a lesser magnitude 85 which prevents overheating of the valve structure.

19. In a rectifying system, a source of alternating electro-motive-force and an associated load circuit including solid imperfect 90 valve structure exhibiting little or no polarization, the number of valves in series being such that there tends to flow an inverse current of excessive heating effect, inductance of such magnitude in said circuit that the inverse current is limited to a substantially 95 lesser magnitude, and means for artificially cooling said valve structure cooperating with said inductance in preventing excessive heating thereof.

20. In a rectifying system, a source of alternating electro-motive-force and an associated load circuit including solid imperfect 105 valve structure exhibiting little or no polarization, the number of valves in series being such that there tends to flow an inverse current of excessive heating effect, inductance in said circuit of a magnitude which limits the inverse current to a lesser magnitude which prevents overheating of the valve structure, and an element actuated by the magnetic field of at least a portion of the inductance 110 of said circuit.

21. In a rectifying system, a source of alternating electro-motive-force and an associated load circuit including solid imperfect 115 valve structure exhibiting little or no polarization, the number of valves in series being such that there tends to flow an inverse current of excessive heating effect, and inductance in said circuit of a magnitude which limits the inverse current to a lesser magnitude which prevents overheating of the valve structure, the impedance of said circuit being 120 of such magnitude that the current density is increased without overheating of the valve structure by the co-action of said inductance.

22. In a rectifying system, a source of alternating electro-motive-force and an associated load circuit including solid imperfect 125

- valve structure exhibiting little or no polarization, the number of valves in series being such that the impressed electro-motive-force per valve is substantially greater than the impressed electro-motive-force per valve when the number in series is such that insubstantial inverse current flows, and inductance in said circuit of a magnitude to limit the inverse current to a value which prevents overheating of the valve structure. 5
23. In a rectifying system, a source of alternating electro-motive-force and an associated load circuit including solid imperfect valve structure exhibiting little or no polarization, the number of valves in series being such that the impressed electro-motive-force per valve is substantially greater than the impressed electro-motive-force per valve when the number in series is such that insubstantial inverse current flows, and inductance in said circuit of a magnitude to limit the inverse current to a value which prevents overheating of the valve structure, the ratio of reactance to resistance external to the valve structure being at least unity. 10
24. In a rectifying system, a source of alternating electro-motive-force and an associated load circuit including solid imperfect valve structure exhibiting little or no polarization, the number of valves in series being such that the impressed electro-motive-force per valve is substantially greater than the impressed electro-motive-force per valve when the number in series is such that insubstantial inverse current flows, and inductance in said circuit of a magnitude to limit the inverse current to a value which prevents overheating of the valve structure, the fall of potential across the impedance external to the valve structure being at least as great as the fall of potential across the valve structure. 15
25. In a rectifying system, a source of alternating electro-motive-force and an associated load circuit including solid imperfect valve structure exhibiting little or no polarization, the number of valves in series being such that the impressed electro-motive-force per valve is substantially greater than the impressed electro-motive-force per valve when the number in series is such that insubstantial inverse current flows, inductance in said circuit of a magnitude to limit the inverse current to a value which prevents overheating of the valve structure, and an element actuated by the magnetic field of at least a portion of the inductance of said circuit, the ratio of reactance to resistance external to the valve structure being at least five. 20
26. In a rectifying system, a source of alternating electro-motive-force and an associated load circuit including solid imperfect valve structure exhibiting little or no polarization, the number of valves in series being such that the impressed electro-motive-force per valve is substantially greater than the impressed electro-motive-force per valve when the number in series is such that insubstantial inverse current flows, and inductance in said circuit of a magnitude to limit the inverse current to a value which prevents overheating of the valve structure, and which effects a ratio of forward to inverse current of at least two. 25
27. In a rectifying system, a source of alternating electro-motive-force and an associated load circuit including valve structure of the copper-cuprous oxide type, the number of valves in series being such that there tends to flow an inverse current of excessive heating effect, and inductance in said circuit of a magnitude which limits the inverse current to a lesser magnitude which prevents overheating of the valve structure. 30
28. In a rectifying system, a source of alternating electro-motive-force and an associated load circuit including valve structure of the copper-cuprous oxide type, the number of valves in series being such that there tends to flow an inverse current of excessive heating effect, and inductance in said circuit of a magnitude which limits the inverse current to a substantially lesser magnitude and permits a current density of at least $\frac{1}{3}$ ampere per square inch of rectifying surface without overheating of the valve structure. 35
29. In a rectifying system, a source of alternating electro-motive-force and an associated load circuit including valve structure of the copper-cuprous oxide type, the number of valves in series being such that there tends to flow an inverse current of excessive heating effect, inductance in said circuit of a magnitude which limits the inverse current to a lesser magnitude which prevents overheating of the valve structure, and means for artificially cooling the valve structure to effect materially greater current density without overheating of the valve structure. 40
30. In a rectifying system, a source of alternating electro-motive-force and an associated load circuit including solid imperfect valve structure, said valve structure being further of the character that the inverse current rapidly increases with small increase of inverse voltage, the number of valves in series being such that the inverse current is of a magnitude rapidly increasing to a value adapted to cause substantial deterioration of the valve structure with small increase of inverse voltage, and inductance in said circuit of a magnitude which limits the inverse voltage to a magnitude below that at which the inverse current rapidly increases as aforesaid, to prevent substantial deterioration of the valve structure. 45
31. The combination with a source of alternating current of a load circuit, solid imperfect valve structure exhibiting little or no polarization included in said circuit, the number of valves in series being less than the number of valves in series being such that the impressed electro-motive-force per valve when the number in series is such that insubstantial inverse current flows, and inductance in said circuit of a magnitude to limit the inverse current to a value which prevents overheating of the valve structure, and which effects a ratio of forward to inverse current of at least two. 50

ber of valves in series to effect insubstantial inverse current, and inductance effective in said circuit of a magnitude for maintaining the temperature of the valve structure below that at which it rapidly deteriorates while permitting said valve structure to conduct greater load current than permissible without overheating.

32. The combination with a source of alternating current, of a load circuit, solid imperfect valve structure exhibiting little or no polarization included in said circuit, and inductive reactance associated with said valve structure, the number of valves in series being such that in the absence of said reactance inverse current of excessive heating effect flows, said reactance having such magnitude that the inverse current is of a magnitude to permit said valve structure to pass greater load current than otherwise permissible without overheating.

33. The combination with a source of alternating current, of a load circuit, solid imperfect valve structure exhibiting little or no polarization included in said circuit, means for artificially cooling said valve structure, and inductive reactance associated with said valve structure, the number of valves in series being such that in the absence of said reactance inverse current of excessive heating effect flows, said reactance having such magnitude that the inverse current is of a magnitude to permit said valve structure, when cooled by said cooling means, to pass greater load current than otherwise permissible without overheating.

34. The combination with a source of alternating current, of imperfect valve structure, an inductive reactance and resistance in series therewith, said reactance having such great magnitude with respect to said resistance that the ratio of direct to inverse current is at least two, and said ratio, resistance, reactance, and number of valves in series having the relation

$$y^n \alpha = Z$$

wherein y is said ratio, n is an exponent whose magnitude depends upon the characteristics of the valve, α is K times the ratio of the resistance to reactance, where K is the line voltage or voltage drop across the impedance external to the valve structure divided by the number of valves in series, and Z is a constant.

35. The combination with a source of alternating current, of copper-cuprous oxide valve structure, an inductive reactance and resistance in series herewith, said reactance having such great magnitude with respect to said resistance that the ratio of direct to inverse current is at least four, and said ratio, resistance, reactance and number of valves in series having the relation

$$y^n \alpha = Z,$$

wherein y is said ratio, n is an exponent of the order of 2, α is K times the ratio of the resistance to reactance, where K is the line voltage or voltage drop across the impedance external to the valve structure divided by the number of valves in series, and Z is a constant of the order of 250.

36. The combination with a source of alternating current of valve structure of the copper-cuprous oxide type in circuit therewith, the number of valves in series being such that substantial inverse current tends to flow, and inductance in said circuit for limiting the inverse current to a substantially lesser magnitude, the ratio of inductive reactance to resistance external to said valve structure being at least ten, the ratio of forward to inverse current being at least six, and the fall of potential for the load current across the impedance external to the valve structure having a magnitude at least four times the fall of potential across said valve structure.

37. The combination with a source of alternating current of valve structure of the copper-cuprous oxide type in circuit therewith, the number of valves in series being such that substantial inverse current tends to flow, inductance in said circuit for limiting the inverse current to a substantially lesser magnitude, the ratio of inductive reactance to resistance external to said valve structure being at least ten, the ratio of forward to inverse current being at least six, and the fall of potential for the load current across the impedance external to the valve structure having a magnitude at least four times the fall of potential across said valve structure, and means actuated by the magnetic field of at least a portion of the inductance of said circuit for performing mechanical work.

38. In the art of rectification by imperfect valve action, the method which comprises impressing a voltage of such magnitude upon imperfect valve structure of such number of valves in series that said voltage divided by the number of valves in series is greater than the breakdown voltage per valve, and applying inductive reactance, effectively in series with said valve structure, of magnitude to prevent injury to said valve structure.

39. In a rectifying system, the combination with a source of alternating voltage and imperfect valve structure comprising such number of imperfect valves in series that said voltage divided by the number of valves in series is greater than the breakdown voltage per valve, and inductance, effectively in series with said valve structure, of magnitude to prevent injury to said valve structure.

40. The combination with a source of alternating current, of a load circuit, imperfect valve structure, the number of valves in series being such that there tends to flow inverse current of such magnitude as to cause substantial deterioration of the valve struc-

ture, and an inductive translating device, effectively in series with said valve structure in said load circuit, for performing mechanical work and whose inductive reactance varies in 5 performance of the work, the inductance of said circuit notwithstanding said variation of reactance of said device limiting the inverse current to a substantially lesser magnitude.

In testimony whereof I have hereunto affixed my signature the 30th day of April, 1930.

CARL S. WEYANDT.
